UNITED STATES PATENT OFFICE.

GEORGE BONNELL, OF CHICAGO, ILLINOIS.

CODE-BOOK.

1,372,797.

Specification of Letters Patent. Patented Mar. 29, 1921.

Application filed July 9, 1920. Serial No. 395,102.

To all whom it may concern:

Be it known that I, GEORGE BONNELL, a citizen of the United States, residing at Chicago, in the county of Cook and State of Illinois, have invented certain new and useful 5 Improvements in Code-Books, of which the following is a specification.

This invention relates to a code book for use in the transmission of numbers by telegraph and it is especially adapted for the 10 use of railroads and other industries in referring to the numbers of cars and the like.

The principal object of the invention is to 15 provide an improved code book having an improved arrangement of code words and numbers therein for securing efficiency and economy in the use of the telegraph or any other form of communication. The invention is adapted to overcome the necessity of 20 transmitting car numbers, for example, by the use of a separate word for each figure of the number, and an important feature of the invention is the use and arrangement of words which permit the numbers to be codified 25 readily and insure a correspondingly rapid translation of the codified number.

The improved code book comprises a series 30 of numbers ranging from 1 to 999, and these numbers are arranged in columns in numerical order so that any number of one or two or three figures can be located in its proper 35 place in the book. The code words used for transmitting these numbers are ordinary and usual words such as are found in the dictionary, and these words are selected and arranged in alphabetical order, the words progressing alphabetically with the numerical progression of the numbers so that any word can be readily located in the code book by 40 reason of this alphabetical arrangement. The alphabetical arrangement of the words extends through several letters of the words so that a large number of the words beginning with a single letter of the alphabet can 45 be used for designating a corresponding series of numbers.

A person desiring to transmit any number 50 of six figures, for example, examines the code book and selects the words which correspond to the figures or groups of figures which make up the number. Thus in codifying a six figure number it is desirable to 55 select words corresponding to two groups of three figures each so that the number can be transmitted by means of two words. In

translating the codified number, the operator merely refers to the parallel columns in the code book.

All of the numbers from 1 to 999 and corresponding code words are arranged in parallel columns of Section One of the code book. The book also comprises Section Two which contains a series of code words for transmitting corresponding numbers which consist partially or wholly of ciphers. This 60 section of the book will be referred to for transmitting numbers or parts of numbers including ciphers, and also for transmitting numbers in which ciphers precede or follow other numbers of the figure. This section of 65 the book also includes a number of additional code words which can be used for transmitting any other desired information. Section Three of the code book consists of a list of code words and a parallel arrangement of 70 corresponding fractional numbers which are arranged in numerical order. The three sections of the book and the numbers and figures embodied therein are arranged as shown 75 in the accompanying drawings: 80

In the accompanying drawings a small extract from each section of the book is illustrated, the dotted lines between successive words and numbers in the columns being used to indicate that certain numbers and 85 words in the series have been omitted. Several columns of numbers and words appear on each page of the book and these numbers are continued in numerical progression on the successive pages. 90

The use of this code book will be readily understood by those skilled in the art. If one desires to codify the number 189961 for example, the operator refers to the code book and selects the word "Awake" corresponding 95 to the group of figures 189 and the word "Fair" corresponding to the group of figures 961. The number can then be transmitted by telegraphing the code word as follows: "Awake Fair." In a similar manner the number 289488 can be codified and transmitted by using the words "Betide Careen," the number 346000 will be represented by the words "Blush Flay," and the number 1321091 will be represented by the 100 words "Aback Blast Giddy." It will be observed that the word "Flay" representing three ciphers has been selected from Section Two of the book and also the word "Giddy" which represents the figures 091. All of the 110

other words in the examples just mentioned have been selected from Section One of the code book. Any number can thus be codified, including fractional numbers without the necessity of paying any attention to decimal points.

When transmitting a series of separate numbers in a continuous list, where no word or other character intervenes between separate numbers, the word "And" is used to separate the numbers, thus:

"Acorn and Avow Armor and Chirp Choir."
(21) (187145) (534536)

15 Where the number to be stated is the double of any figure or figures such as 2929, this number should be codified by repeating the reference word for 29 twice "Adept Adept." A six figure number comprising 20 two similar groups of three figures each would be transmitted in a similar manner, for example, the number 139139 would be codified as "Argus Argus."

Where the figure 0 is the first or first and 25 second or all three of the last three figures in any number, these numbers will be codified by referring to Section Two of the code book. For example, 10001="Able Floor."

Where prefix letters are a part of any 30 number these should be stated, as they are, in connection with the reference word quoted for the number.

The code book therefore permits the ready codification and the ready translation of the 35 code words due to the novel selection and arrangement of these words and numbers in the code book. A distinguishing feature of the invention is the novel arrangement of the numbers and the words in numerical and alphabetical order, respectively, whereby a 40 person having a number can readily locate the word or words to be used in codifying it and a person receiving the code words can quickly find the corresponding numbers 45 without reference to a key or anything except the code book. The words used are short and are complete words so that they are much more readily understood and transmitted by the telegraph operator than any 50 other system of code words heretofore known.

Although I have shown and described one embodiment of the invention for purposes of illustration, it will be understood that it 55 may be employed in various other ways

without departing from the scope of the appended claims.

I claim:

1. A code book comprising a series of 60 pages having numbers and complete known code words printed thereon in parallel columns, the numbers being arranged progressively in numerical order with one word opposite each number.

2. A code book comprising a number of 65 pages having numbers and code words arranged thereon in parallel columns with one word opposite each number, said numbers and said words being arranged progressively 70 in numerical and alphabetical order respectively, and said numbers being divided into separate sections according to their character.

3. A code book comprising a series of 75 pages having numbers and complete known words arranged thereon in parallel columns with one word opposite each number, said numbers being limited to figures of three digits, and smaller numbers arranged progressively in numerical order, said words being arranged progressively in alphabetical 80 order.

4. A code book comprising a series of 85 pages having numbers and complete known words arranged thereon in parallel columns with one word opposite each number, said numbers being limited to figures of three digits, and smaller numbers arranged progressively in numerical order, said words being arranged progressively in alphabetical 90 order, said book being divided into a plurality of sections, one section comprising integral numbers and the other section comprising fractions.

5. A code book comprising a series of 95 pages having numbers and complete known words arranged thereon in parallel columns with one word opposite each number, said numbers being limited to figures of three digits, and smaller numbers arranged progressively in numerical order, said words 100 being arranged progressively in alphabetical order, said book being divided into a plurality of sections, one section comprising integral numbers, another section comprising fractions, and another section comprising 105 integral numbers preceded by zeros.

In testimony whereof, I have subscribed my name.

GEORGE BONNELL.
